PUMP

Louis M. Cotchett, Hingham, Mass., assignor to
 Textile Patent & Process Company, Boston,
 Mass., a corporation of Massachusetts

Application September 13, 1933, Serial No. 689,243

5 Claims. (Cl. 299—97)

The present invention relates to hand-operated pumps and the like, which have particular adaptation for the atomization of fluids such as cleaning fluids, perfume, insecticides and others. The 5 pump is readily adaptable to a compact form of fluid container, and operates with greater efficiency and less likelihood of deterioration than the usual form of pump or rubber bulb atomizer employed for such a purpose.

10 The various features consist in certain novel features of construction, combinations and arrangements of parts more particularly described hereafter and set forth in the accompanying claims.

15 In the drawing illustrating the preferred form of the invention, Fig. 1 is a side elevation of a fluid container and applied atomizing or pumping unit; and Fig. 2 is an elevation in section upon an enlarged scale of the same unit illustrating the internal construction of the pump element.

20 Referring particularly to the illustrated embodiment of the invention, the fluid may be contained in a suitable form of container such as a 25 glass member 10, having a ribbed top portion 12 closed by a detachable cap 14 threaded to the top at 16 to approximately seal the container. The pumping element is mounted directly in the cap 14 through the provision of a guide sleeve 18 de-

30 pending centrally of the cap and locked thereto by a disk 20 received in a shouldered portion of the sleeve, and by a spun-out flange 22 engaging with the opposite side of the cap, as will be self-evident. Sliding freely within the sleeve is a 35 hollow plunger 24, provided with an internal chamber 26 vented at its upper end through an atomizing plug 28 sealed within the plunger and having an atomizing vent 30 in the outer end. The interior of the plug is in free communication 40 with the chamber 26, which is normally closed

45 at its lower end by a ball check valve 32, resting upon a seat 34 formed in a plug 36. The plug is capable of sliding within the chamber 26, and is normally retained in the lowermost position shown in the drawing by a coil spring 38, the downward movement being limited by an in-turned shoulder 40 formed on the plunger.

50 Connected with the plug 36 and projecting downwardly from the pump unit is a replenishing tube or inlet connection 42 of sufficient length to extend approximately to the bottom of the container as indicated, the tube having an opening 44 to admit liquid thereto even though the end of the tube contacts with the bottom.

55 In practice, after the assembly is mounted upon

the container, depression of the plunger by pressure upon the surface 50 contracts the chamber 26 and causes fluid therein to be ejected forcibly through the atomizing jet 30, the ball 32 seating to prevent egress from the chamber in this direction. Upon release of the plunger 50 and return by the spring 38, sufficient suction is created to draw fluid upwardly through the tube 42 and ball check 32 to replenish the chamber interiorly. Thereafter depression of the plunger 60 again ejects fluid, and the operation may be repeated as desired.

65 It will be evident that with this construction the element may be readily interchanged between containers, is compact, fool-proof, and by proper 70 formation of the cap may be applied to any form or size of container. The pump is particularly adaptable to containers of small volume which are portable and may be held in the hand for directing the atomizing jet as desired.

75 When not in use the upward movement of the plunger 24 under the action of the spring 38 is limited by an out-turned shoulder 52, which engages with the lower end of the guide sleeve 18. Obviously this upward movement may be caused 80 by engagement of the tube 42 with the bottom of the container, causing the spring 38 to thrust upwardly on the surrounding plunger.

75 What is claimed is:

1. The combination with a container designed 85 as a fluid reservoir of a cap detachably closing the container, a hollow plunger forming a chamber sliding in the cap and carrying a delivery outlet from the chamber to atmosphere, a fluid conducting tube extending from the interior of 90 the plunger into the container and slidably engaged with the plunger to replenish the plunger interiorly, and means for resiliently moving the plunger in a direction to expand the chamber therewithin.

95 2. The combination with a fluid container of a cap detachably sealing the container, a guide sleeve on the cap, a hollow plunger sliding within the sleeve and providing an expandable chamber, an atomizing outlet connecting the chamber with atmosphere, a fluid lead-in tube communicating with said container and slidably connected with the chamber of the plunger at the inner end, a valve for closing communication between the chamber and the lead-in tube on movement inwardly of said plunger, and a spring mounted in the chamber for normally maintaining the chamber expanded.

100 3. A fluid pumping unit comprising a hollow plunger forming a chamber, a guide within which 110

- the plunger slidably moves, means for slidably closing the chamber within the plunger at one end, a fluid inlet communicating with the slid-
able closure, a spring in the chamber for normal-
ly maintaining the slidable closure at the end
of the chamber, an outlet from the opposite end
of the chamber, and a valve for closing communi-
cation with the inlet upon contraction of the
chamber within the plunger.
- 10 4. The combination with a fluid container of a
detachable closure for the container, a chambered
plunger slidably mounted upon the closure and
having a delivery opening to atmosphere at the
outer end, a fluid lead-in tube within the con-
tainer and extending to the inner end of the
plunger, means for slidably sealing the lead-in
tube to the interior of the plunger to close the
chamber therein, means within the chamber of
the plunger for normally thrusting the lead-in
tube against the container to provide a fixed base
against which the chamber can be contracted,
- 5 and a valve closing the inlet tube on contraction
of the chamber.
5. The combination with a liquid container of
a closure therefor, a hollow plunger slidably
mounted in the closure and closed at its outer end
except for the provision of a restricted delivery
outlet connecting a chamber within the plunger
to atmosphere, a liquid lead-in tube slidably sup-
ported at the inner end of the plunger to close
the chamber therewithin, means upon the plunger
for maintaining the connected end of the lead-in
tube from disengagement from the plunger, a
spring supported within the chamber of the
plunger for normally expanding the chamber by
moving the plunger outwardly with respect to the
lead-in tube, and a valve for closing communi-
cation between the lead-in tube and plunger
chamber upon movement of the plunger to con-
tract the chamber.
